Attorney.

UNITED STATES PATENT OFFICE

MAURICE LEMAIRE, OF MARCINELLE, BELGIUM

DEVICE FOR THE EXHAUST OF THE STEAM FROM LOCOMOTIVE ENGINES

Application filed August 30, 1929, Serial No. 389,529, and in Belgium August 31, 1928.

The present invention relates to a device for the exhaust of the steam from locomotive steam engines, that is to say, a device or apparatus which is fixed to the free extremity 5 of the exhaust pipe and by means of which the exhaust steam enters the smoke box of the boiler.

In such cases, where the locomotive is provided with several funnels it will have as 10 many such devices as it has chimneys.

In this case, the invention relates to each of the devices for the exhaust, that is to say to each device which terminates the exhaust pipe corresponding to each funnel.

15 Exhaust devices are already known which comprise a nozzle terminating the exhaust pipe, the said nozzle being in some cases divided into several parts or divisions by means of dividing walls or partitions.

20 Various types of devices are also known, by means of which a much better subdivision of the steam jet is obtained and by means of which the exhaust steam is forced into the smoke box in the form of several jets.

25 According, however, to the present invention, the nozzles fixed at the free end of the exhaust pipes, and by means of which the steam enters the smoke box in the form of several jets, are separated and at a certain 30 distance from one another, so as to leave on the inside of the crown or bunch that they form, as well as in the interior of the crown or bunch of steam jets, spaces which are free of steam, to which the smoke has easy access 35 by passing between the nozzles.

Experience shows that this device allows a greater cross section of free space for the issue of the steam, and yet, notwithstanding this fact, the same amount of draft is obtained, and it thus becomes possible to obtain a much lower exhaust pressure at the cylinder exhaust ports than the exhaust pressure obtainable with the known exhaust devices, a fact which, all other conditions being equal, 40 increases the output and the efficiency of the locomotive.

45 It has already been proposed for the fact of achieving the same result and obtaining thus the same advantages, to interpolate between the exhaust device proper and the fun-

nel a great number of devices of various kinds, the purpose of which was to subdivide the single jet flowing through them, and several of these devices comprise several nozzles arranged at a certain distance from one another, and thus providing an interspace between themselves which is free of steam, to which spaces the smoke or the combustion gases have access by passing between the nozzles.

These devices, however, are offering on the one hand a great resistance to the exhaust flow of the steam, because the latter has already attained by its expansion at the mouth or outlet orifice of the exhaust a considerable 55 kinetic energy, and on the other hand this expansion itself is much less efficiently made use of for the induction to flow of the smoke.

For the purpose of being able to regulate the amount of smoke able to pass between the nozzles the apparatus or device is according to the invention either provided with a sleeve surrounding the whole group of nozzles, and the position of which can be regulated in relation to the latter for instance by means of 70 displacing it in the mean direction of the group of nozzles, or by admitting a certain variable quantity of steam into the interspace between the individual nozzles.

Other details and characteristic features 75 will be mentioned in the course of the description of the drawings annexed to the present specification.

These drawings show a few of the constructional forms, as diagrams and possible 80 examples.

Figures 1 and 2 show a device for the exhaust according to the invention, in perspective partially in section and with the sleeve for regulating the amount of smoke passing 85 between the nozzles in two different positions.

Figure 3 shows a device for controlling or adjusting the above mentioned sleeve.

Figure 4 shows also in perspective and 90 partially in section another embodiment of a device for the regulation of the quantity of smoke passing between the nozzles.

In referring to Figure 1, the device comprises a steam exhaust pipe 2, which is pro- 95

vided at one end with a certain number of nozzles 3, arranged in a bunch or crown, and which are separated from one another in such a manner that the smoke or combustion gases, in the smoke box, into which the steam exhaust device has been fixed, can easily completely surround these nozzles by following the path shown by the arrows in Figure 1. They can thus have ample and easy access to the central steam free space which exists at the interior of the crown or bunch formed by the nozzles.

For the purpose of being able to regulate the quantity of smoke or combustion gases passing between the nozzles there is provided according to the invention in the constructional form shown in Figures 1 and 2 a sleeve 4 which surrounds the nozzles 3 and is mounted in such a manner that its position can be adjusted or varied in relation to the nozzles.

The above mentioned sleeve 4 consists of a cylindrical ring which can be displaced in the direction of the centre line of the nozzles, for instance, until it reaches the position shown in Figure 2.

When the sleeve 4 reaches this latter position it is impossible for the combustion gases or smoke to reach the central space in the interior of the nozzle, by reason that the individual jets of the exhaust steam issuing from these nozzles reunite immediately above the sleeve 4. The gases are then only carried along or induced by the exterior surface of the steam jets.

For the purpose of being able to displace or adjust the sleeve 4 in the manner mentioned above, it is sufficient to provide a control member of any kind whatever which is accessible from the driver's platform, and which may, for instance consist of a lever 5 actuating a bell crank lever 6 one of the arms of which is provided with a slot or groove 6a into which a pin or button 4a engages, which is fixed to the sleeve 4.

It would, however, also be possible to provide in place of the devices shown in the preceding figures, an arrangement to fill the space between the nozzles with steam for the purpose of preventing access of the smoke or combustion gases to the interior of the crown or bunch of nozzles.

This steam may be admitted by opening an orifice 7 which is provided between the nozzles 3 and which would, for the purpose of closing it, be provided with a valve 7a, which could be operated in any desired manner from the outside.

The space in the interior of the crown formed by the nozzle being more or less filled with steam, the quantity of smoke or combustion gases able to pass through it would thus be correspondingly reduced. Moreover this additional opening 7 would have the effect of increasing the cross sectional area for the passage of steam and achieves thus in

addition to the effect just mentioned, the usual advantages appertaining to an exhaust variable by means of altering the cross sectional area of the steam passage.

It is of course evident that the invention is not strictly limited to the constructional forms mentioned, and that numerous modifications may be made in the form, shape and arrangement of the component parts suitable for carrying the invention without thereby departing from the scope of the invention. It may be combined with any or all known devices such as the "petticoats", the "Kilala blowers", etc.

What I claim is:

1. A device for the exhaust of the steam of locomotive engines, comprising a plurality of nozzles adapted to direct the exhaust into the smoke box of the boiler and grouped to provide a steam free space therebetween for the passage of the combustion gases in the smoke box and adjustable means to prevent at times the combustion gases entering the said steam free space.

2. A device for the exhaust of the steam of locomotive engines, comprising a plurality of nozzles arranged to provide a free space centrally thereof for the combustion gases in the boiler smoke box and manually operable valve means to permit of the exhaust steam entering the free space to regulate the amount of combustion gases entering the free space.

3. A device for the exhaust of the steam of locomotive engines, comprising in combination with the steam exhaust pipe of the locomotive engine positioned in the smoke box thereof, a plurality of nozzles grouped to provide a free space therebetween, the grouped nozzles being provided with an opening disposed centrally thereof, and valve means operable to open or close the opening disposed centrally of the nozzles to regulate the amount of combustion gases entering the free space between the same.

In testimony thereof I have hereunto signed my name.

MAURICE LEMAITRE.
